(57) **CLAIM**

The ornamental design for portable, waterproof, shock resistant, wireless speaker, as shown and described.

DESCRIPTION

FIG. 1 is a top, front, right side perspective view of a portable, waterproof, shock resistant, wireless speaker showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view thereof along line 8-8 in FIG. 5; and,

FIG. 9 is a cross-sectional view thereof along line 9-9 in FIG. 2.

Representative recesses in some squares of the larger recess grids shown in FIGS. 3 and 7 are shaded to represent the same recesses in every such square.

The squares of the smaller square grids in FIGS. 1, 2, and 3 represent holes in those squares.

The broken lines in the drawings illustrate environmental material that forms no part of the claimed design.
